UNITED STATES PATENT OFFICE.

DAVID A. CARSON, OF WILKINSBURG, PENNSYLVANIA.

ATTACHMENT FOR BEDS.

No. 926,849.

Specification of Letters Patent.

Patented July 6, 1909.

Application filed October 10, 1908. Serial No. 457,079.

To all whom it may concern:

Be it known that I, DAVID A. CARSON, a citizen of the United States of America, residing at Wilkinsburg, in the county of Allegheny and State of Pennsylvania, have invented certain new and useful Improvements in Attachments for Beds, of which the following is a specification, reference being had therein to the accompanying drawing.

10 This invention relates to improvements in attachments for beds, and the object of my invention is to provide a bed extension that can be used as a crib or for increasing the width of a bed, whereby a single bed can be conveniently used by two persons.

15 My invention aims to provide a collapsible extension that can be easily and quickly set up and secured to a bed to provide a strong and durable structure and when not in use 20 can be folded and placed under the bed. In this connection my attachment is particularly designed for iron and brass beds, and in appearance is adapted to harmonize with the finish of the bed in connection with which 25 the same is used.

The detail construction of my invention will be presently described and reference will now be had to the drawing, wherein,

Figure 1 is a perspective view of a bed 30 equipped with an attachment in accordance with this invention, Fig. 2 is a cross sectional view of the same, and Fig. 3 is an end view of the attachment collapsed.

In the accompanying drawings, 1 and 2 35 designate the head and foot pieces of the bed respectively, connected together by side rails 3.

40 My attachment comprises a rectangular metallic body 4 having one side thereof provided with a longitudinal rail 5 and the ends thereof provided with rails 6. The rail 5 is provided with two yokes 7 for engaging one of the side rails 3 of the bed, while the ends of the rails 6 adjacent to the longitudinal 45 rail 5 are provided with depending bearings 8 for rollers 9, these bearings and rollers serving to support one side of the attachment when the same is collapsed. The rails 6 support foot and head pieces 10, each piece having outer posts 11 connected by a side piece 12. Hinged to the upper ends of the posts 11 is a side frame 13 provided at the upper 50 edges thereof with sockets for a purpose that will presently appear. Hinged to the head and foot pieces 10 are head and foot frames 15 adapted to engage in the sockets and be

held in a vertical position by the vertical position of the side frame 13. The preferable form of socket consists of a sleeve movably mounted upon the pin 16 carried by the side frame 13, said sleeve being moved to engage a projection 17 forming part of each head and foot piece. Hinged to the lower ends of the posts 11 are legs 18 connected by a longitudinal rod 19. The legs 18 are provided with casters 20 similar to the bed and adjacent to the hinged ends thereof with auxiliary casters 21, these casters acting in conjunction with the bearings 8 and the rollers 9 for supporting the attachment in a collapsed condition and for facilitating the movement of said attachment.

The side frame 13 is connected to the rail 6 by collapsible links 22 and the legs 18 are connected to said rails by collapsible links 23, 75 these links serving to maintain the side frame 13 and the legs 18 in vertical alinement. For holding the side frame 13 and the legs 18 in a folded position, as will presently appear, the rails 6 are provided with 80 pivoted resilient straps 24 having hook-shaped ends 25 adapted to be sprung into engagement with the legs 18 and the ends of the frame 13. The yokes 7 permit of the attachment being easily and quickly removed 85 from the bed, and by shifting the sleeves 14 the end frames 15 can be folded downwardly. By collapsing the links 22 and 23, the side frame 13 and the legs 18 can be folded inwardly and held by the straps 24. With the 90 legs 18 folded inwardly, the auxiliary casters 21 and the rollers 9 assist in moving the attachment, which when collapsed is adapted to be placed under the bed. The yokes 7 permit of the attachment being used in connection with beds of various types, and as illustrated in the drawing, the attachment is constructed of iron and designed particularly for iron and brass beds.

It is thought that the utility of my attachment will be fully understood and while in the drawings there is illustrated the preferred embodiments of my invention, it is obvious that the structural elements thereof can be varied or changed, as to shape, proportion and manner of assemblage without departing from the spirit of the invention.

Having now described my invention what I claim as new is:—

1. A foldable attachment for beds comprising a frame embodying side and end rails, connecting members carried by one of

the side rails of said frame and adapted to engage one of the side rails of the bed for coupling the attachment thereto, rollers carried by the said end rails, posts connected to 5 said frame at one side thereof, head and foot pieces connected to said frame and said posts, end frames hinged to said head and foot pieces, a side frame hinged to the upper ends of said posts, legs hinged to the lower 10 ends of said posts, rollers supported at right angles with respect to the legs and associating with the first mentioned rollers when the attachment is folded and shifted, collapsible braces attached to said side rails and to said 15 legs, collapsible braces connecting said side frame to said end rails, and means for detachably connecting the end frames to the side frame.

2. A foldable attachment for beds comprising a frame embodying side and end rails, connecting members carried by one of the side rails of said frame and adapted to engage one of the side rails of the bed for coupling the attachment thereto, rollers carried by the said end rails, posts connected to 20 said frame at one side thereof, head and foot pieces connected to said frame and said posts, end frames hinged to said head and foot pieces, a side frame hinged to the upper 25 ends of said posts, legs hinged to the lower ends of said posts, rollers supported at right angles with respect to the legs and associating with the first mentioned rollers when the attachment is folded and shifted, collapsible 30 braces attached to said side rails and to said legs, collapsible braces connecting said side frame to said end rails, means for detachably connecting the end frames to the side frame, and resilient pivoted straps carried by the end rails and adapted to engage 35 the ends of the side frames and said legs for maintaining the side frame and legs in a closed position when the attachment is folded.

45 3. A foldable attachment for beds comprising a rectangular frame embodying side and end rails, yokes carried by one of the side rails and adapted to engage with a bed for

coupling the attachment thereto, rollers supported by said end rails, posts secured to the 50 frame, head and foot pieces carried by the end rails, folding end frames hinged to said head and foot pieces, a folding side frame hinged to the upper ends of said posts and adapted to be detachably connected to said 55 end frame, legs hinged to the lower ends of said posts, rollers carried by said legs and adapted to coöperate with said first mentioned rollers when the attachment is folded and shifted, collapsible links attached at one 60 end to said end rails and at the other end to said legs, collapsible links attached at one end to said side frame and to said end rails, said links when extended constituting braces for said legs and said side frame. 65

4. A foldable attachment for beds comprising a rectangular frame embodying side and end rails, yokes carried by one of the side rails and adapted to engage with a bed for coupling the attachment thereto, rollers supported by said end rails, posts secured to the 70 frame, head and foot pieces carried by the end rails, folding end frames hinged to said head and foot pieces, a folding side frame hinged to the upper ends of said posts and 75 adapted to be detachably connected to said end frame, legs hinged to the lower ends of said posts, rollers carried by said legs and adapted to coöperate with said first mentioned rollers when the attachment is folded and shifted, collapsible links attached at one 80 end to said end rails and at the other end to said legs, collapsible links attached at one end to said side frame and to said end rails, said links when extended constituting braces 85 for said legs and said frame, and means carried by said rectangular frame for maintaining said side frame and legs in a folded position.

In testimony whereof I affix my signature 90 in the presence of two witnesses.

DAVID A. CARSON.
